WRINGER

Horace H. Beasley, North Bergen, N. J.

Application October 3, 1942, Serial No. 460,713

6 Claims. (Cl. 68—244)

This invention relates to new and useful improvements in wringers. This is a continuation-in-part of my co-pending application, Serial No. 405,739, filed August 7, 1941, now Patent No. 2,311,811 issued February 23, 1943.

One object of the invention comprises, inter alia, a non-fouling wringer. Another object of the invention comprises such a wringer for use as an accessory to a self-contained washing unit for the washing of dishes, pots, pans and other household utensils.

These and other objects and advantages of the invention will appear from the following description read in conjunction with the drawings, in which:

Fig. 1 is a front elevation partly fragmentary and partly in section of a unit having thereto attached a wringer in accordance with the invention;

Fig. 2 represents a section of Fig. 1 on the line 2—2;

Fig. 3 illustrates a section of Fig. 1 on the line 3—3;

Figs. 4 and 7 are side and rear elevations respectively, partly in section, of a wringer in accordance with the invention;

Fig. 5 is a front elevation of the wringer unit shown in Figs. 4 and 7;

Fig. 6 represents a top plan view of the wringer unit shown in Figs. 4, 5 and 7; and

Fig. 8 illustrates a perspective view showing the details of the frame structure of the wringer in accordance with the invention, indicating the wringer rolls and the flat-spring in dotted outline.

Specifically referring to the drawings, a container or receptacle A for housing the power drive, similar to that shown in said Patent No. 2,311,811 above referred to, is secured to an adjustable sink engaging support comprising a sleeve B adapted to slidably receive the horizontally disposed leg B' of the supporting or anchoring member C. The lower end of the member C has pivotally mounted thereon a member D for accommodating itself to and engaging a wall of a conventional sink E. The outer or engaging face of the member D preferably has a rubber facing F to increase the effective grip. The relative position of the leg B' of the member C may be controlled by a suitable setscrew G. A second sleeve H is mounted parallel to and connected with the sleeve B, the ends of the sleeves B and H being offset as indicated. The sleeve H is adapted to slidably receive the horizontally disposed leg J of the downwardly bent supporting member K. The

lower end of the leg K has pivotally mounted thereon a sink engaging rubber faced member L similar to the member D. The horizontally disposed leg J of the member K is adjustably secured in various positions in the sleeve H by a thumb or setscrew M. The receptacle A is largely supported by the sink engaging members C and K and the sleeves B and H. Vertically adjustable rod N having a bent foot O adapted to rest on the back of the sink affords with the members C and K a three point support for receptacle A. The use of separate sleeves for each of the supporting members C and K arranged in parallel relation with their ends projecting relatively to each other permits a greater range of adjustability and rigidity than a single sleeve while at the same time, together with the bracket N and footing O, affording adequate support for the motor drive unit housed in the cabinet A.

A suitable operating head Q driven by a power unit housed in receptacle A and connected therewith by a flexible shaft (power unit and shaft not shown) is adapted to engage various operating tools. The operating head is shown by dotted outline in Fig. 2 as engaging a wringer, which is illustrated more particularly in Figs. 4 to 8.

The wringer shown in Figs. 4 to 8 comprises cooperating frame structures mounting spindled rollers R and S respectively. As illustrated in the figures the wringer assembly frame leg S' is rigidly secured to leg S'' by yoke 19. Leg S' extends upwardly beyond leg S'' and may be inserted rotatively and slidably in extension bracket sleeve 12 (Fig. 4) being adjustably securable therein by set screw 22.

Forming a rigid part of the wringer frame assembly S', 19, S'' are two arms 16 and 16'. As illustrated in Fig. 5 arm 16' may be integrally connected to yoke 19 while arm 16 may be carried as an integral part of frame leg S'. Arms 16—16' carry cut-outs to form half bearings to receive and rotatably support the spindle R' in roller R. The spindle R' extends upwardly beyond supporting arm 16 and is provided (Figs. 4 and 6) with a laterally extending key member R'' positioned and adapted to lock with operating head Q.

The cooperating frame member which houses and supports roller S includes arms U and U' held in rigidly spaced position by connecting bar U''. Cross arm U is pivotally mounted relative to frame leg S'' by the cut-out forming half bearing 30. Cross arm U' is pivotally mounted with respect to frame leg S'' by means of bolt 21 securing the cross arm U' on the lower end of leg S''. The cross arms U and U' are provided

with cut-outs forming half bearings intermediate their ends to rotatably support the spindle of roller S. The movable frame assembly, including cross arms U and U' and connecting bar U'', is thus rotatable with respect to the frame leg S'' and by reason of spring T slotted at either end to engage studs 10 and 11 on arms U and U' causes roller S to be resiliently pressed against roller R, pressure on spring T at its central point being maintained by the finger T' mounted on leg S'' being secured thereto by a set screw 23.

The space between leg S' and the upper or free end of leg S'' is completely unobstructed by any supporting, bridging, or other structure. This structurally open end of the wringer thus permits the material to be acted upon by the wringer to be fed to and between the revolving rollers from this open unobstructed end.

The wringer (Fig. 1) is supported by an adjustable bracket unit rigidly secured by way of member X to the leg sleeves B and H. The bracket arm member M (Fig. 1) is rigidly connected to sleeve 12, which is adapted to engage and secure the wringer and is slidably adjustable with respect to the slotted end of the arm member M' being secured thereto by screw 15. The opposite relatively flat end of member M' is with its centrally located screw hole movably engaged by the bracket clamp formed by member X (Fig. 1) which is rigidly secured to leg sleeves B and H (Fig. 2). Member X extends slightly beyond leg sleeves B and H and is folded backward forming the lower jaw X' of the clamp. A suitable clamping grip is maintained on arm M' by screw 17 between jaws X' and X'' on member X. A slotted concave spring washer 31 is provided (Fig. 3). Screw 17 is threaded in lower jaw X' on member X. The pivoted bracket arm M mounting the wringer, resists frictionally a limited swingable effort, thus frictionally securing the wringer in or out of operating position.

As illustrated in the drawings (Figs. 1 and 2) the washing unit may be provided with suitable means to support the operating head Q in accessible position. For this purpose the supporting hook W, having indent W', is provided, the same being vertically adjustable on member X, which is secured in any convenient manner to the sleeves B and H to afford a rigid support in supporting various tools in operating position. The hook member W may be secured in desired position in any convenient manner as by setscrew 14.

The foregoing description is by way of illustration and not of limitation, and it is therefore my intention that the invention be limited only by the appended claims or their equivalent wherein I have endeavored to claim broadly all inherent novelty.

It is claimed:

1. A wringer comprising a substantial U-shaped, substantially rigid frame, a first and second wringer roll, two first cross arms, positioned

and shaped to rotatably support therebetween said first wringer roll and substantially rigidly secured to one of the legs of said frame, and two second cross arms, positioned and shaped to 5 rotatably support therebetween said second wringer roll in cooperating position with said first wringer roll and pivotally hinged against spring force in substantially rigidly spaced relation to the other leg of said frame for substantially resilient cooperation between said first and second wringer rolls.

2. A wringer comprising a substantially U-shaped substantially rigid first frame, a first and second spindled wringer roll, two first cross arms 15 substantially rigidly secured to one of the legs of said first frame, each carrying spindle bearing means and both positioned to rotatably support therebetween in said bearing means the spindle of said first wringer roll, a second frame carrying said second wringer roll and pivotally hinged to the other leg of said first frame, and spring means for resiliently pressing said second frame into cooperative position between said first and second wringer rolls, said second frame including two 20 second cross arms each pivotally hinged at one end to said other leg, a rigid spacer arm securing the other ends of said second cross arms in rigidly spaced relation, spindle bearing means intermediate the ends of said second cross arms, said 25 second wringer roll being rotatably supported with its spindle between said second cross arms and the bearings therein.

3. A wringer in accordance with claim 2 in which said spring means include a flat spring 30 secured to said second frame and a fixed finger secured to said first frame and having its end pressing on said spring.

4. A wringer comprising a first member, a first wringer roll, first means on said first member for 40 rotatably supporting said first wringer roll at either end thereof, a second member rigidly secured to said first member on only one end thereof and extending in spaced relation thereto, a second wringer roll and second means on said 45 second member for rotatably supporting said second wringer roll at either end thereof in cooperating position with said first wringer roll.

5. A wringer comprising a substantially rigid U-shaped structure, a first and second wringer roll, first means on one of the legs of said U structure for rotatably supporting said first wringer roll at either end thereof, and second means on the other leg of said U structure for 50 rotatably supporting said second wringer roll at either end thereof in cooperating position with said first wringer roll.

6. A wringer in accordance with claim 5 in which said second means are pivotally hinged with respect to said other U leg against spring 55 pressure for resilient cooperation between said first and second wringer rolls.

HORACE H. BEASLEY.
